STANCHION FOR STORING AN ELECTRICAL CORD AND THE LIKE

David Y. Mulkey, 6 Main Place,
Arlington, Tex. 76010

Filed Mar. 24, 1972, Ser. No. 238,025

Term of patent 14 years

Int. Cl. D8—06

U.S. Cl. D8—220

FIG. 1 is a perspective view of a stanchion for storing an electrical cord and the like, as viewed from the right front;

FIG. 2 is an elevation view of the stanchion as seen from the rear;

FIG. 3 is an elevation view of the stanchion as seen from the front;

FIG. 4 is a top view of the device;

FIG. 5 is a bottom view of the device;

FIG. 6 is an elevation view showing the left side of the stanchion;

FIG. 7 is a cross-sectional view of the device taken on line 7-7 of FIG. 3; and

FIG. 8 is another perspective view, the broken lines being for illustrative purposes only.

I claim:

The ornamental design for a stanchion for storing an electrical cord and the like, as shown and described.
